UNITED STATES PATENT OFFICE.

LELAND L. FOSS, OF VIDALIA, GEORGIA, ASSIGNOR OF ONE-HALF TO MOSES LEADER,
OF VIDALIA, GEORGIA.

COTTON-GIN OF THE DOUBLE-ROLLER TYPE.

1,215,137.

Specification of Letters Patent.

Patented Feb. 6, 1917.

Application filed January 25, 1916. Serial No. 74,206.

To all whom it may concern:

Be it known that I, LELAND L. Foss, a citizen of the United States, residing at Vidalia, in the county of Toombs, State of Georgia, have invented certain new and useful Improvements in Cotton-Gins of the Double-Roller Type; and I do hereby declare the following to be a full, clear, and exact description of the invention, such as 10 will enable others skilled in the art to which it appertains to make and use the same.

This invention relates to cotton gins of the double roller type which are designed to force the seeds from the cotton without 15 breaking the fibers of the cotton.

An object of the invention resides in the provision of a machine which is so constructed that it will have the maximum operating capacity or so that the relation of 20 its operating capacity to that of the ordinary single roller gin will be as four is to one and that of the double roller gin as two is to one.

This object is attained broadly by the provision of a pair of spaced rollers, a ginning blade for each, a pair of oscillatory stay bars, each of which carries a pair of hacker blades which coöperate with the rollers and means for imparting an alternate movement 30 to the stay bars.

A further object of the invention resides in the provision of integral stay bars which support the hacker blades rigidly and without any additional means such as tie rods.

35 A further object of the invention resides in so constructing the stay bars that the upper edges of the hacker blades lie in a plane just above the longitudinal axis of the pivot for the stay bars.

40 A further object of the invention resides in so constructing the machine that the driving or operating mechanism will be so located that it will not be exposed to the dirt incident to the ginning operation.

45 Another object of the invention resides in the provision of novel means for clamping the ginning blades to the breasts.

Another object of the invention resides in the provision of novel means for adjusting 50 the position of the ginning blades so that the pressure of the blades upon the rollers will be uniform.

A further object of the invention resides in the provision of improved journal boxes

for the rollers so that the rollers may be 55 properly adjusted.

Another object of the invention resides in the provision of improved tension devices for maintaining the ginning blades normally in their operative positions. 60

A further object of the invention resides in the provision of improved means for supporting the breasts.

Finally an object of the invention resides in means for supporting the crank shaft so 65 that it will be subjected to the minimum amount of wear and resistance.

With these and other objects in view, such as will appear as my description progresses, my invention comprises the combination 70 and arrangement of parts as set forth in and falling within the scope of the appended claims.

In the drawing:

Figure 1 is a perspective view of a machine constructed in accordance with my invention;

Fig. 2 is a front elevation thereof;

Fig. 3 is a plan view, parts thereof being broken away to more clearly disclose the 80 mechanism;

Fig. 4 is a vertical transverse sectional view taken on line 4—4 of Fig. 3 looking in the direction of the arrow and showing the breasts, the stay bars, with the blades on 85 each, the feeder operating mechanism and the griddles;

Fig. 5 is an end elevation;

Fig. 6 is a similar view looking at the opposite end of the machine and showing the 90 driving mechanism;

Fig. 7 is a perspective view of one of the stay bars, and

Fig. 8 is a fragmental detail showing the manner of adjusting the connecting rod. 95

The embodiment of the invention disclosed in the drawing includes a pair of spaced end plates 1 which are held in fixed relation by rods 2 on which are nuts 3 and 4, the former being located on the inside of the plate and 100 the latter on the outside thereof. These end plates are adapted to rest upon a suitable support 5 such as a floor or the like.

Extending between these end plates 1 and through the same are shafts 6 on which are 105 secured rollers 7 having the usual leather facings 8, which rollers are disposed between the end plates. These shafts are mounted in

suitable bearings 9 supported by the end plates and secured to the ends of the shafts are pulleys 10 and 11. These bearings 9 are carried by bars 9', which bars are supported by bolts 10', the bolts passing through the ears 17 and having nuts 11' adjustable on their upper ends so that the bars 9' may be adjusted vertically. The lower ends of the bars are secured to the end plates 1 by bolts 12' which extend through slots 13' in the bars and are rigid with the end plates. These bolts 12' also act as pivots for the bars 9' and the bars may be moved about their pivots by means of bolts 14' which extend through ears 15' on the end plates and are provided with nuts 16'. These bolts are slideable in slots 17' in the ears 15' and are pivotally connected to the bars 9' by rivets 18'. Thus the rollers may be adjusted either vertically or horizontally. In order that these rollers may be revolved in opposite directions, I have provided a line or driving shaft 12 on which a drive pulley 13 is secured. A belt 14 passes around this drive pulley 13, over the pulley 10 beneath the pulley 11 and over an idler 15 which is supported by means of a bracket 16 on the adjacent end plate. The end plates 1 are provided with ears 17 at their upper edges from which ears bolts 18, having eyes 19 on their lower ends, depend, which bolts are supported, adjustably, by means of nuts 20 and are located adjacent each end of each of the rollers. A breast 21 is located adjacent each of the rollers 7, being oscillatably supported by trunnions 22 which are formed on the ends of the breasts and pass through the eyes 19 on the rods 18, the eyes being held in place upon the trunnions by washers 23 and lock-nuts 24. These breasts are provided with longitudinally extending dove-tail rabbets 25. Adjustably secured to the breasts 21 by means of a plurality of bolts 26 are plates 27 which coöperate with the rabbets to form slots. Located in these slots and extending downwardly therefrom are ginning blades 28 which are wedge shaped in formation and are adapted to be clamped in place upon the breasts by the plates 27. The blades are made in this particular form and held upon the breasts in this manner so that they may be adjusted and clamped in place irrespective of the wear thereon. These blades extend downwardly in the usual manner and contact with the faces of the rollers. Extending upwardly from the breasts 21 are arms 29 and 30, the arms being secured in place on the breasts by suitable bolts 31. The upper end of the arm 29 is provided with ears 32 and pivoted between these ears is a rod 33 which extends to the arm 30 and passes between the ears 34 which are formed thereon and which ears have notches 35 in the edges remote from the arm 29. Slidably mounted upon this rod 33 is a block 36 having trun-

nions 37 on the opposite sides thereof, which trunnions are located in the notches 35. The adjacent end of this rod 33 is screw threaded and engaged with these screw threads is a nut 38 by means of which the effective length 70 of the rod may be varied, that is to say, the distance between the upper ends of the arms 29 and 30 may be varied. Bolts 39 having eyes 40 thereon, which eyes surround the trunnions 22 of the breasts, are provided, 75 which bolts extend horizontally and through ears 41 formed on the end plates 1. These bolts are slideable through the ears 41 so that the trunnions 22 may be drawn closer to or moved away from the ears to vary the pivotal point of the breast with relation to the rollers. The bolts are held in their adjusted position by means of nuts 42. It will be seen that by operating the nuts 20 the breasts may be adjusted vertically. The pressure or 80 tension of the ginning blades 28 upon the rollers 7 may be varied by adjusting the nuts 42 on the bolts 39 and the nut 38 on the rod 33 so that the upper ends of the arms 29 and 30 will be pulled together and the pivots of 90 the breasts will be moved in opposite directions which will impart to the breasts, a twisting motion, forcing the lower edges of the ginning blades tighter upon the rollers.

In order that the ginning blades may be 95 normally pushed downwardly resiliently, I have provided each of the rods 18 with an extension 43. Extending between these rods and resting upon the extensions, at each end of the machine, is a bar 44 from which projects a vertical bolt 45 which extends through and is slideable in an ear 46 on the adjacent end plate of the machine. Disposed between the plates 46 and the bar 44 is a coil spring 47 which normally forces 100 the bar downwardly, the movement of the bar being limited by the nuts 20. These ginning blades are pressed downwardly, resiliently, so that when they are struck by the hacker blades, which will later be described, they will not be nicked or broken.

Mounted on each end plate 1 is a bearing 48 and extending between the end plates is a supporting member 49 which is provided with a bearing 50 similar to the bearings 48, 115 in alignment with and disposed midway between the same. In order that the seeds may be pushed from the cotton, I have provided a pair of stay bars each of which has a trunnion 51 mounted in the intermediate bearing 50 and a trunnion 52 mounted in one of the bearings 48. The trunnion 52 is provided with a crank portion 53 on which is a crank arm 53' and the crank portions on the two trunnions extend in opposite direction, that is to say, one hundred and eighty degrees from each other. These stay bars are each made of one casting which includes a central bar 54 from which the trunnions 51 and 52 extend and arms 55 which extend at right 120 angles to the central bar 54. The stay bars 49 are each 125 made of one casting which includes a central bar 54 from which the trunnions 51 and 52 extend and arms 55 which extend at right angles to the central bar 54. The stay bars 49 are each 130

angles to the central bar 54 and between the ends of which a hacker blade support 56 extends, which support is provided with a plurality of spaced bolt receiving holes. These supports 56 are each in the form of an angle iron and the hacker blades 57 are mounted thereon, being held in position by bolts 58 which pass therethrough and through the said holes in the supports. It is to be noted that the arms 55 are so located with respect to the central bar 54 or to the longitudinal axis of the trunnions that the upper edges of the hacker blades 57 will be in a plane about one inch above the plane which includes the upper edges and the aforementioned longitudinal axis of the trunnions. These hacker blades are carried in this particular manner so that their movement will be such that the seeds will be forced from the cotton without a shearing action such as would occur if the upper edges of the blades were above or below the aforementioned plane. Movement is imparted to these stay bars in the following manner:

Extending between and mounted in bearings on the end plates 1 is a shaft 59 which is provided with oppositely extending crank portions 60 and 61 on the ends thereof. This shaft is rotated by means of a belt 62 which passes over a pulley 63 on the line shaft 12 and over a pulley 64 on itself. Connected to each of the crank portions 53 on the stay bars, is a link 65 which is pivoted at 66, to a second link 67. This link 67 is pivoted, at 68 to a plate 69. The plate 69 is adjustable vertically and horizontally on the adjacent end plate 1, the adjustment being had by means of bolts 70 which pass through slots 71 in the end plate and slots 72 in the plate 69. The link 65 is provided with an angularly extending arm 73 to which is connected a rod 74, which rod is pivotally connected to the adjacent crank portion on the shaft 59. Referring particularly to Fig. 8 of the drawing it will be seen that the rod 74 is of peculiar construction, that is to say, it is made in two sections 75 and 76, the section 75 having a tongue 77 thereon and the section 76 having a socket 78 therein into which the tongue 77 extends. The tongue is however shorter than the socket and a wedge pin 79 is disposed between the same, which pin may be forced into the socket to move the sections apart and held in position by a set screw 80. Surrounding these sections is a strap iron 81 which is provided at its ends with bearing portions 82 of Babbitt or other suitable metal. Disposed between this Babbitt bearing portion and the end of the adjacent section is a complementary bearing portion 83, which bearing portions receive the pivot 66 and the adjacent end of the shaft 59. It will be seen therefore that as the bearing portions wear the sections 75 and 76 may

be forced apart by the wedge 79 and the bearings tightened. This movement is permitted by the screws 84 which secure the strap 81 to the sections and pass through slots 85 in the strap. The link 67 is formed in the same manner and it is therefore not deemed advisable to describe this link in detail. The upper end of the link 65 is formed in somewhat a similar manner, that is to say, it is identical with one half of the link 74, the bearing members being omitted from one end and the strap being secured by means of a bolt 86. When the shaft 59 is actuated the links 74 on the ends of the machine will be reciprocated because of their connection to the crank portions 60 and 61 of the shaft and this reciprocation of the links 74 will be opposite and will cause the breaking of the links 65 and 67 at their pivot points 66 so that the cranks 53 on the ends of the stay bars will be oscillated. This oscillation of the stay bars will cause the blades carried thereby to be alternately raised and lowered and as they pass the ginning blades, the cotton seed will be forced from the cotton. In connection with the cranks 53 and the crank arms 53' it is to be noted that the crank arms extend in angular relation to the horizontal when the links 65 and 67 are in alinement with each other. The effect of this is that when the links 65 and 67 are broken about their pivots 66 the crank arms will be drawn to a position below the horizontal, when they are again moved into alinement with each other the crank arms will be moved above the horizontal and when they are broken to the opposite side of the vertical the crank arms will again be moved below the horizontal. It will thus be seen that upon each revolution of the driving shaft 59 each of the hacker blades will be moved past the ginning blades twice. This produces a rapid operation of the hacker blades and inasmuch as four of these blades are provided the maximum speed of operation will be attained.

In order that the cotton may be fed to the ginning blades and the rollers and the seeds taken care of after having been forced from the cotton, I have secured, adjustably to the inner face of each end plate, a support 87, the adjustment being had by means of bolts 88 which pass through slots 89 in the supports. A shed board 90 is mounted on these supports and extends between the same and supported by horizontal arms 91 of the supports are seed griddles 92 which are located adjacent the rollers 7 but sufficiently spaced therefrom to permit the hacker blades to pass the same and the rollers. These seed griddles are provided with a plurality of perforations 93 through which the seeds may drop after having been expelled from the cotton. Slidably mounted

on each seed griddle is a feeder 94 which reciprocates on the upper face of the seed griddle, the feeders being secured together at their ends by means of rods 95 so that as 5 one feeds the cotton to the roller or ginning blade the other will be withdrawn to receive a fresh supply of cotton.

In order that these feeders may be reciprocated, I have provided a shaft 96 which 10 extends through the end plates 1 and is mounted in bearings 97. One end of this shaft is provided with a pulley 98 over which a belt 99 extends, which belt also extends over a pulley 100 on the shaft 6 on which the 15 pulley 10 is mounted, being held tightly on this pulley by an idler 101. Connected to this shaft 96 are links 102 which are connected to staples 103 carried by one of the feeders. Thus as the shaft 96 is rotated, 20 through the pulleys 98 and 100 and the belt 99, the feeders will be successively and alternately moved toward and away from the rollers and the cotton fed to the same. Each 25 of these links 102 includes a pair of sections which are secured together by a strap 104, the strap passing over and forming a bearing for the shaft 96. The other end of the link is provided with a strap 105 by means of which the link is attached to the staple 30 103.

By way of summary it is stated that I have provided a double roller cotton gin in which one ginning blade co-operates with each roller and I have mounted the breasts 35 which carry the ginning blade in such manner that the pressure of the blades upon the rollers may be varied and so that the breasts may be adjusted vertically to vary the position of the blades with relation to the 40 rollers. Furthermore I have so mounted the breasts that they will be forced downwardly by resilient means which will permit them to ride if the ginning blades are struck by the hacker blades so that neither the ginning 45 blades nor the hacker blades will be injured.

I have mounted the rollers in such manner that they may be adjusted vertically or horizontally independently of the ginning 50 blades. Furthermore I have provided the machine with two stay bars each of which carries a pair of hacker blades, one blade co-operating with each roller. These blades are so mounted that as one blade rises to 55 force the cotton seed from the cotton the diagonally opposite blade will have a like movement while at the same time the remaining blades will move downwardly or away from the ginning blades to permit the latter to receive a fresh supply of cotton. By this construction the capacity of the 60 machine over those of the ordinary types is greatly increased. I have so constructed the adjusting means for the rollers and 65 breasts that a uniform pressure may be at-

tained throughout the entire extent of the ginning blades which is a pre-requisite to the successful ginning of the cotton.

While I have illustrated and described a particular embodiment of my invention, it 70 has merely been for the sake of convenience and I do not wish to be limited to that particular embodiment as it is obvious that numerous changes may be made in the details of construction without departing from the 75 spirit of the invention or exceeding the scope of the appended claims.

What I claim is:—

1. In a cotton gin, end frames having vertical and horizontal slotted flanges, a ginning roller, a breast having end trunnions, and upwardly extending arms, a ginning blade carried by said breast and adapted to contact tangentially with said roller, and means for adjusting said breast bodily and 80 arcuately to adjust said blade with relation to said roller from its tangential contacting line with the roller as a center, including intersecting vertical and horizontal bolts engaging slots of said flanges and in 85 the inner intersecting ends of which said trunnions are mounted, and nuts threaded upon the outer ends of said bolts and engaging said flanges and a transverse lengthwise adjustable rod connecting said arms. 90

2. In a cotton gin, end frames having vertical and horizontal slotted flanges, a ginning roller, a breast having end trunnions, and upwardly extending arms, a ginning blade carried by said breast and adapted to contact tangentially with said roller, and means for adjusting said breast bodily and arcuately to adjust said blade with relation to said roller from its tangential contacting line with the roller as 100 a center, including intersecting vertical and horizontal bolts engaging slots of said flanges and in the inner intersecting ends of which said trunnions are mounted, nuts threaded upon the outer ends of said bolts 105 and engaging said flanges and a transverse lengthwise adjustable rod connecting said arms, said vertical bolts having lateral extensions, and spring means engaging said lateral extensions for resisting upward 110 movement of said breast and the ginning blade carried thereby.

3. In a cotton gin, end frames having vertical and horizontal slotted flanges, a ginning roller, a breast having end trunnions, and upwardly extending arms, a ginning blade carried by said breast and adapted to contact tangentially with said roller, and means for adjusting said breast bodily and arcuately to adjust said blade 120 with relation to said roller from its tangential contacting line with the roller as a center, including intersecting vertical and horizontal bolts engaging slots of said flanges and in the inner intersecting ends 125 130

of which said trunnions are mounted, nuts threaded upon the outer ends of said bolts and engaging said flanges, and a transverse lengthwise adjustable rod connecting said 5 arms, and spring means engaging said lateral extensions for resisting upward movement of said breast and the ginning blade carried thereby, and means for adjusting said rollers bodily in two directions including vertical bars carrying said rollers and having lower slots, bolts carried by said end frames and engaging said lower slots, upper vertical bolts engaging slots of said horizontal flanges, at their lower ends having 10 pivotal engagement with said bars and from which said bars and said rollers are suspended, and horizontal bolts engaging slots of said vertical flanges and at their inner ends pivotally engaging said bars, and nuts 15 threaded upon the outer ends of said vertical and horizontal bolts and engaging said flanges.

4. In a double roller cotton gin, end

frames having vertical and horizontal slotted flanges, ginning rollers, breasts provided with end trunnions and upwardly extending arms, ginning blades carried by said breasts and adapted to contact tangentially with said rollers, intersecting vertical and horizontal bolts engaging the slots 25 of said flanges and having at their inner intersecting ends eyes in which said trunnions are mounted, said bolts having at their outer ends nuts threaded thereon and engaging said flanges, a transverse lengthwise 30 adjustable rod connecting said upwardly extending arms, a transverse bar engaging said vertical bolts, and spring means for exerting pressure upon said bar.

In testimony whereof, I affix my signature, in the presence of two witnesses.
